Philip Beckley
Design of Snivel Hook

5041

PATENTED JUN 27 1871

Fig. 1.

Fig. 2.

UNITED STATES PATENT OFFICE.

PHILIP G. BECKLEY, OF NEWARK, NEW JERSEY.

DESIGN FOR SWIVEL AND SNAP-HOOK.

Specification forming part of Design No. 5,041, dated June 27, 1871.

To all whom it may concern:

Be it known that I, PHILIP G. BECKLEY, of Newark, in the county of Essex and in the State of New Jersey, have invented certain new and useful Improvements in Design for Swivel and Snap-Hook; and do hereby declare that the following is a full, clear, and exact description thereof, reference being had to the accompanying drawing and to the letters of reference marked thereon making a part of this specification.

The nature of my design is fully illustrated by the accompanying drawing.

A represents a hook pivoted in a bent bar, B, the ends of said bent bar being connected by a

rod or pin, C, as shown. A part of the hook is incased in a movable sheath or covering, D, of sheet metal, the spring *a* being fastened to the inside of the sheath and to the hook, as shown in Figure 1.

What I claim is—

The design for swivel-hook, as shown and described.

In testimony that I claim the foregoing I have hereunto set my hand this 1st day of May, 1871.

PHILIP G. BECKLEY.

Witnesses:

A. N. MARR,
JOHN N. KERR.
